PLAY MAT FOR CHILDREN

Otto Pascal, Brooklyn, N. Y.

Application February 24, 1954, Serial No. 412,255

1-Claim. (Cl. 2—69)

This invention relates to a mat adapted to be placed upon a floor, whether the floor be covered with a rug or not, the mat being particularly designed as a play mat for children, and being novelly shaped and formed in such a manner as to provide a great attraction for the child or children who are to use the same.

It is well appreciated that in many instances, a child will tend to play upon the floor at a particular location particularly attractive to him. For example, many children are accustomed to viewing television programs for substantial periods of time, and under these circumstances, the child will tend to sit upon the floor in a particular location relative to the television set.

This is undesirable in many instances, in view of the fact that the child may have with him various playthings which, if carelessly used, may cause damage to a rug. For example, crayons, paints, and similar possessions of the child would fall within this category, it being apparent, accordingly, that it is desirable to provide the child with a play mat which can be spread upon the floor at a location found particularly suitable.

It is important, as will be appreciated, that a play mat of the type stated be made as attractive as possible to the child, to encourage use of the mat by the child.

Accordingly, in view of the above, it is an important object of the present invention to so design a child's play mat as to make the mat particularly attractive to the child, thereby affording not only a comfortable resting place for the child while viewing a television program, but also, a protective covering for a rug or floor surface.

To this end, a mat formed in accordance with the present invention is preferably shaped in an outer configuration simulating the skin of an animal, such as a zebra, tiger, leopard, etc. Further, it is proposed to so design the mat constituting the present invention as to permit its being reversed side for side, with the mat having one side in the simulation of the skin of a particular animal, and the other side in the simulation of the skin of a different animal.

Still further, the invention, in another embodiment thereof, may have ties which are normally concealed when the mat is spread face up upon a rug or floor surface. Such ties, however, can be utilized whenever desired to fasten the mat to the head, arms, and legs of the child, so that the child may derive amusement from imitation of the animal represented by the design of the mat.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective view of a mat formed in accordance with the present invention.

Fig. 2 is an enlarged, detail sectional view taken substantially on line 2—2 of Fig. 1.

2

Fig. 3 is a bottom plan view of a modified form of mat formed in accordance with the present invention.

Fig. 4 is an enlarged, detail sectional view taken substantially on line 4—4 of Fig. 3.

5 Fig. 5 is a sectional view taken on line 5—5 of Fig. 3, on an enlarged scale.

The reference numeral 10 has been applied generally in Figs. 1 and 2 to the play mat constituting the present invention, and as shown in Fig. 1, the mat is formed in an outer configuration approximating that of the skin of an animal, as for example, a bear, leopard, or the like. Thus, the mat is provided with a wide, relatively elongated body 12 having an area sufficient to accommodate one or more children sitting thereupon, and is also provided with arms 14, feet 16, a head 18 and a tail 19.

Additionally, buttons 20 can be sewed to the head 18 of the mat, in transversely spaced relation, to approximate the eyes of the animal. These can, of course, be omitted if desired in the form of the invention shown in Figs. 1 and 2.

Preferably, the mat is of quilted, padded construction, so as to provide a convenient support for the child which will be found comfortable when the child sits upon the mat for extended periods of time. To this end, the mat 25 is formed with plastic or cloth cover sheets 22, 24, which confine between them a selected thickness of conventional padding 26. The covering sheets and padding can be quilted as at 28, to increase the attractiveness of the mat and to hold the padding in place without danger of said padding becoming lumpy or uncomfortable in particular areas.

The entire mat is bound at its periphery by a length of binding 30, which is stitched to the edge portions of the sheets 22, 24 by stitching 32.

35 At this point, it should be noted that in a preferred embodiment of the invention, the binding 30, as well as the sheets 22, 24 would be formed of waterproof material, so as to permit rough usage of the mat without shortening the life thereof. Further, the use of waterproof material permits the mat to be washed off with ease, whenever necessary.

It will be appreciated that one of these sheets can be provided with a design intended to simulate the skin of a particular animal, while the other sheet can be provided 45 with a different design, intended to simulate the skin of another animal. One sheet might, for example, be designed as the skin of a zebra, while the opposite sheet can be designed as the skin of a leopard.

In Figs. 3—5, a modified form of mat has been shown, 50 designated generally by the reference numeral 34. In this form of the invention, the outer configuration of the mat is substantially the same as in the first form, the mat including a body 36, a head, tail, and legs. Further, so far as the basic construction of the mat is concerned, the modified form is similar to that previously described herein, in that is, a pair of opposed sheets are adapted to confine between them a supply of cotton padding, with said sheets and padding being quilted and the padding being confined at the edges of the sheets by a length of suitable binding.

55 In the form of the invention shown in Figs. 3—5, however, the mat is adapted particularly for use as a covering for the child, if the child desires to imitate the animal represented by the mat.

To this end, the head and the four legs are each provided with a pair of ties which are normally buttoned under the mat in the manner shown in Fig. 3, so as to remain concealed when the mat is simply being used as a floor covering on which the child can rest. Thus, the head portion is provided with a pair of ties 38, said ties having their outer ends stitched to the opposite side edges of the head by the binding of the mat. The inner ends of the ties, that is, those ends remote from the anchored

or stitched ends are provided with buttonholes, to permit their being engaged by buttons 40. The buttons 40 are provided on the underside of the mat, opposite buttons 41 provided on the upper face of the mat. It will be understood, in this regard, that in Figs. 3-5 the mat is shown inverted. The top surface of the mat will not be provided with ties, and thus, when the mat is turned face up, only the buttons 41 will show, the buttons 41 simulating eyes in the same manner as the buttons 20 of the first form.

The ties 38 are preferably crossed as shown in Fig. 3, and connected to the buttons 40 when said ties are not in use.

Referring to Figs. 3 and 5, each of the legs is provided with a button 42 disposed midway between the opposite side edges of the leg in spaced relation to the outer end of the leg. The button 42 of each leg is adapted to engage the free ends of a pair of ties 44 provided upon each leg on the underside thereof.

The ties 44 are stitched at one end under the binding of the mat, by peripheral stitching 46, the binding being designated by the reference numeral 48. Each tie is, of course, provided with a buttonhole 50 at that end thereof remote from the stitched end, the buttonhole being utilized whenever the tie is to be attached to its associated button.

The buttons 42 can be provided only upon the underside of the mat, if desired, or alternatively, can oppose buttons 52 on the upper surface of the mat, the buttons 42, 52 being attached to the mat by a common securing thread 54.

As previously noted herein, the ties 44, 38 will normally remain concealed on the underside of the mat when the mat is being used as a rest by the child. When, however, the child cares to place the mat over him, the ties 38, 44 can be disengaged from their associated buttons 40, 42 respectively, after which the ties 38 can be tied about the child's head, with the head portion of the mat overlying the back of the child's head. The ties 44 on those legs of the mat nearer the head portion of the mat would be tied about the wrists of the child, while the ties 44 on the rear legs would be tied about the child's ankles. In this way, the mat will cover the child, while remaining attached to the child's head, arms, and legs, and the child can, on all fours, derive pleasure from the article by imitating the particular animal simulated by the sheet design of the top surface of the mat.

A mat formed in accordance with the invention can, of course, be manufactured at a relatively low cost, considering the attractiveness thereof and the long use to which it can be effectively put. The mat has, as an important characteristic, a construction which is intended to provide

particular appeal to the child, and as will be readily understood, the child can turn up either face of the mat to blend with the story of a particular television program which he or she may be viewing.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A play mat for children comprising a flat four-cornered flexible padded body, said body having extending portions outwardly of its edge at its corners and having an extending portion outwardly of its edge intermediate one pair of corners, said body and extending portions defining a contour in simulation of the contour of the body of an animal when spread flatwise, said intermediate extension simulating the head of the animal, said pair of cornered extensions on both sides of the intermediate extension simulating the fore legs of the animal, the other pair of cornered extensions simulating the rear legs of the animal, a pair of spaced buttons secured to the head-simulating portion on one side of the body in simulation of the eyes of the animal, the other side of the body having a pair of spaced buttons on the head-simulating portion in alignment with the eye-simulating buttons and having a button substantially at the juncture between each leg-simulating portion and the body portion, a pair of ties fastened to the head-simulating portion, said ties having one end fastened to opposed edges of said head-simulating portion, and a pair of ties fastened to each leg-simulating portion, said latter ties having one end fastened to opposed edges of each leg-simulating portion, said ties having holes in the unattached ends adapted to receive and engage the buttons on the respective head and leg simulating portions.
